(57) **CLAIM**

We claim the ornamental design for a generator, as shown and described.

DESCRIPTION

FIG. 1 is a top, front, left perspective view of the claimed design according to a first embodiment;

FIG. 2 is a top, rear, left perspective view thereof;

FIG. 3 is a front elevational view thereof;

FIG. 4 is a rear elevational view thereof;

FIG. 5 is a left side elevational view thereof;

FIG. 6 is right side elevational view thereof;

FIG. 7 is a top plan view thereof; and,

FIG. 8 is a bottom plan view thereof.

The broken lines shown in the views are included for the purpose of illustrating portions of the generator that form no part of the claimed design.

1 Claim, 8 Drawing Sheets
